The ornamental design for an instrument housing, as shown and described.

DESCRIPTION

FIG. 1 is a perspective view of an instrument housing.

FIG. 2 is a front view of the instrument housing of FIG. 1.

FIG. 3 is a right side view of the instrument housing of FIG. 1.

FIG. 4 is a left side view of the instrument housing of FIG. 1. FIG. 5 is a top view of the instrument housing of FIG. 1; and, FIG. 6 is a rear view of the instrument housing of FIG. 1. The broken lines illustrate portions of the instrument housing that form no part of the claimed design.
